FIG. 6

FIG. 7

FIGURE 1 is a top plan view of a vibrato tailpiece for stringed instruments, showing our design;

FIGURE 2 is a side elevational view;

FIGURE 3 is an opposite side elevational view;

FIGURE 4 is a front end elevational view with the adjustable handle in a different position;

FIGURE 5 is a rear end elevational view with the handle in the same position as in FIGURE 4;

FIGURE 6 is a bottom plan view, a portion of the handle being broken away for convenience of illustration; and

FIGURE 7 is a fragmentary side elevational view, partly in cross-section taken on line 7-7 in FIGURE 1, a portion of the handle being omitted for convenience in illustration.

The fragmentary broken line showing of a representative stringed instrument in FIGURE 1 is for illustrative purposes only.

We claim:

The ornamental design for a vibrato tailpiece for stringed instruments, as shown and described.
